UNITED STATES PATENT OFFICE.

CORNELIUS B. CORCORAN, OF NEW YORK, N. Y., ASSIGNOR TO UNDERWOOD TYPE-WRITER COMPANY, OF NEW YORK, N. Y., A CORPORATION OF DELAWARE.

TYPEWRITING-MACHINE.

1,351,327.

Specification of Letters Patent. Patented Aug. 31, 1920.

Application filed January 15, 1919. Serial No. 271,203.

To all whom it may concern:

Be it known that I, CORNELIUS B. CORCORAN, a citizen of the United States, residing in borough of the Bronx, in the county 5 of the Bronx, city and State of New York, have invented certain new and useful Improvements in Typewriting - Machines, of which the following is a specification.

This invention relates to typewriting machines, and more especially to means whereby the beginning of the writing line may be varied. The invention is herein disclosed as applied to an Underwood typewriting machine having one form (somewhat modified) 10 of the usual margin-stop attached thereto, one form of such a stop being illustrated in the patent to Kurowski, No. 948,058.

The device is especially illustrated as adapted to be used in addressing envelops, 20 in which work it is usually desired that the first line shall begin the farthest to the left, the next line not quite so far to the left, etc. To accomplish such variation in the beginning of the writing line, I have found it 25 advantageous to utilize a margin-stop of the general type, indicated above, said stop having associated therewith, on the typewriter carriage, a releasable margin-arresting lever, these parts being well adapted to receive 30 and resist the shock of arresting the typewriter carriage. In order to cause the desired variation of the point at which the carriage is arrested, I have found it advantageous to provide that the margin-release 35 lever may be variously positioned to coöperate with variously located lugs upon the margin-stop.

As herein illustrated, this varying of co-operation may be effected by operation of 40 the line-space lever, and the construction may be such that the line-space lever may be easily rendered ineffective upon the connections. This insures not only that the carriage may travel uninterruptedly until arrested by the right-hand margin-stop, but 45 that the parts coöoperating therewith may be made of any desired strength, since they may be of substantially the same strength and rigidity as those already employed.

50 Other features and advantages will hereinafter appear.

In the accompanying drawings,

Figure 1 is a fragmentary plan view of an Underwood typewriting machine, with

some parts broken away and other parts 55 omitted.

Fig. 2 is a front view of most of the same parts.

Fig. 3 is a section through the mounting of the cam which controls the margin-release lever. 60

Fig. 4 is a perspective view of the slide for operating the cam.

Fig. 5 is a perspective view of the cam and the pawl-and-ratchet connections by 65 which it is operated.

Fig. 6 is a fragmentary perspective view of part of the carriage and part of the frame, showing the parts set to arrest the carriage at the maximum limit of its travel, 70 as determined by the column-stop.

Fig. 7 is a perspective view of an envelop, showing the address thereon.

Fig. 8 is a fragmentary front view of the machine, with the envelop in it while being 75 written and at a point short of the Fig. 6 position for beginning the writing of the second line.

Fig. 9 is a view of some of the parts shown in Fig. 8, but in the act of arresting the carriage just short of the Fig. 8 position for beginning the writing of the third line upon the envelop. 80

Fig. 10 is a perspective view of the margin-stop seen from the rear. 85

Fig. 11 is a rear view, showing the connections between the ratchet wheel and the slide.

In the usual Underwood typewriting machine, the revoluble platen 1 is fast on an 90 axle 2 journaled in a shift frame 3, forming part of the carriage 4. The platen 1 is adapted to be rotated by the usual knob 5 or by the usual line-space lever 6, which is pivoted upon the carriage at 7, and is adapted 95 by means of a bell-crank arm 8 to drive a slide 9 to turn the platen 1, by means of the usual line-space wheel 10, through the usual pawl 11.

An envelop 12, when passed around the platen, is held in position by the usual devices (not shown), so that types 13 on the ends of type-bars 14 may print thereon the characters one after another in addressing the envelop. When a line of writing has 100 been finished, the typist actuates the line-space lever 6, thereby not only causing the platen to rotate but also causing the car- 105

riage 4 to return to the left, under the continued pressure upon the line-space lever, until a margin-release lever 15 brings its lug 16 against a lug 17, of somewhat the usual form, upon a margin stop 18, thus arresting the carriage. Upon release of the line-space lever, it is sprung back to the normal position, seen in Fig. 1, by the usual spring 19.

- 10 In order to enable the margin stop to be compact and strong enough to resist the blow of arresting the carriage, it comprises a barrel 20 partly embracing a shaft 21, and adapted to be held adjusted along the shaft by means of teeth 22, which form part of an arm 23 pivoted at 24 upon a slidable mounting 25. Since the barrel 20 and the lug 17 are rigid with the mounting 25, the stop first holds the lug 17 in arresting position. The teeth 22 may engage with the usual teeth 26 cut upon the shaft 21, and to enable the margin stop to be released, may be swung out of mesh by swinging the arm 23 by means of the usual finger-piece 27.
- 15 25 When the margin-stop has been adjusted by means of its handle 28, which is adapted to be gripped by the finger of the typist when another finger grips the finger-piece 27, the position at which it is set to arrest the carriage is indicated by the usual pointer 29, which overlies the usual scale-plate 30.
- According to the present invention, the margin-release lever has its lug 16 held in position to engage the margin-stop lug 17, because a spring 31 continually presses the lever 15 down against a cam 32. If it is desired to vary the point at which the carriage is arrested by the lug 16 without shifting the margin-stop, the cam 32 may be rotated, with the result that, instead of holding the lug 16 in the position shown in Fig. 6, it will allow the spring 31 to depress the lever to carry its lug 16 to the level of a second lug 33, which is lower down on the same 30 margin-stop and is in advance of the lug 17. According to the present disclosure of the invention, the cam 32 is adapted to be rotated automatically by actuation of the line-space lever, and, for this purpose, the cam is fast to a shaft 34, which is also fast on a ratchet wheel 35, said ratchet wheel being adapted to be turned intermittently by the line-space lever by connections which will now be described. These connections include a slide 36, which lies along the front part of the carriage, and which comprises an adjustable extension 37 adapted to be set so that it will normally lie almost against the line-space lever, with the result that 35 when the line-space lever is actuated, it will carry along the extension 37, the slide 36, and cause a pin 38 upon said slide to turn a plate 39, journaled upon the shaft 34 and provided with a slot 40 in which the pin 38 is adapted to ride. This slot 40 forms,

therefore, a cam by which the slide 36 drives the ratchet wheel 35.

In the usual Underwood typewriting machine, the line-space lever 6 has a uniform throw, and the slot 40 and pin 38 are so adjusted with reference to the shaft 34 that the full stroke of the line-space lever, in the machine disclosed herein, will cause the ratchet wheel to turn a third of a revolution, so that if the ratchet wheel normally holds the cam 32 in the Fig. 6 position, it will turn the cam to the Fig. 8 position upon the next actuation of the line-space lever, and upon the following actuation, will turn the cam to the Fig. 9 position, which permits the catch or lug 16 to drop to a point where it will be arrested by a lug 41 formed upon the barrel or body 20 of the margin stop. This lug 41 will arrest the carriage in position to cause the writing to begin at the proper point in the third line of addressing an envelop. Inasmuch as the cam 32 can make a complete revolution, another actuation of the line-space lever will revolve it from the Fig. 9 position to the Fig. 1 position ready for the insertion of a new envelop.

The connection between the plate 39 and the ratchet wheel 35 is effected by means of a pawl 42, which is adapted to be drawn back rearwardly over the ratchet wheel when the slide 36 is drawn backwardly by the spring 43, which normally tensions it to the right. To hold the pawl 42 normally in position to engage the ratchet wheel, a light spring 44 fast upon the plate 39 overlies it. To enable the extension 37 to be adjusted relatively to the slide 36, the extension is formed as a slide plate running within channels 45 formed upon the slide 36. For convenience in slipping the extension 37 along the slide, it is provided with a finger-piece 46 mounted on a spring 47, which is fast to the extension 37, said finger-piece being provided with a pin 48 extending rearwardly therefrom, and adapted to seat either in an opening 49, which holds the extension in position to be actuated by the line-space lever, or in an opening 50, which holds the extension 37 clear of the line-space lever, even at the limit of its throw. This structure permits the finger-piece 46 to be utilized to actuate the slide for rotating the cam 32 directly, if desired, without actuating the line-space lever.

The slide 36 itself lies behind the usual front bar 51 of the Underwood typewriter carriage, and the connection between it and the extension 37 is formed by an angle plate 52 fast upon the slide 36, and carrying the secondary plate 53, in which the channels 45 are formed. To guide the slide 36, it is provided with a pair of slots 54 and 55, which ride on a pair of shouldered screws 60 and 61 threaded into the bar 51. The screw 61 may serve as an anchorage for the spring 43.

As is clearly shown in Fig. 1, the shaft 34 passes through the front bar 51 and is journaled thereon in any suitable manner against sliding. This may be effected, as shown in Fig. 3, by providing the shaft 34 with a squared section 62 upon which the ratchet wheel 35 fits, so that the ratchet wheel will lie close to the rear face of the bar 51, while the cam 32 lies against the front face of said bar. The plate 39 may be journaled upon an extension 63 of the shaft 34 and be held thereon by a suitable nut 64, which screws up against a shoulder 65 on the shaft 34. In order to enable the typist to see at a glance 10 in what position the typewriter carriage will be arrested, the releasing lever 15 is provided with a scale 66, which includes indications adapted to be read against the top 67 of the end of the bar 51.

20 Variations may be resorted to within the scope of the invention, and portions of the improvements may be used without others.

Having thus described my invention, I claim:

25 1. In a typewriting machine, the combination with a traveling carriage and a line-space lever therefor, of a margin-stop, and means adapted to be variably positioned by operation of the line-space lever to vary the 30 point at which the margin-stop will be effective, independently of the travel of the carriage.

35 2. In a typewriting machine, the combination with a traveling carriage and a line-space lever therefor, of a margin-stop comprising a series of lugs, a coöperating lug on the carriage, and means for variably positioning said coöperating lug by operation of the lever to vary the position at which the 40 other lugs will arrest the carriage.

45 3. In a typewriting machine, the combination with a traveling carriage, of a margin-stop comprising a series of lugs, a lever upon the carriage comprising a lug, and a cam upon the carriage adapted to be variably positioned to vary the position of the lever, to cause its lug to variably coöperate with the other lugs to arrest the carriage.

50 4. In a typewriting machine, the combination with a traveling carriage, of a margin-stop comprising a series of lugs, a lever upon the carriage comprising a lug, a cam upon the carriage adapted to be variably positioned to vary the position of the lever, to cause its lug to variably coöperate with the other lugs to arrest the carriage, and a spring for holding the lever upon the cam.

55 5. In a typewriting machine, the combination with a traveling carriage, of a margin-stop comprising a series of lugs, a lever upon the carriage comprising a lug, a cam upon the carriage adapted to be variably positioned to vary the position of the lever, to cause its lug to variably coöperate with the other lugs to arrest the carriage, and a

line-space lever for variably positioning the cam.

6. In a typewriting machine, the combination with a traveling carriage, of a margin-stop comprising a series of lugs, a lever upon the carriage comprising a lug, a rotatable cam upon the carriage adapted to be variably positioned to vary the position of the lever, to cause its lug to variably coöperate with the other lugs to arrest the carriage, and a line-space lever adapted to rotate said cam through a cycle of positions to bring it to successive points and finally to the initial point.

7. In a typewriting machine, the combination with a traveling carriage and a line-space lever therefor, of a margin-stop, means adapted to be variably positioned by operation of the line-space lever to vary the point at which the margin-stop will be effective, independently of the travel of the carriage, and a device settable to make said means effective at will.

8. In a typewriting machine, the combination with a traveling carriage and a line-space lever therefor, of a margin-stop comprising a series of lugs, a coöperating lug on the carriage, means for variably positioning said coöperating lug by operation of the lever to vary the position at which the other lugs will arrest the carriage, and a device settable to make said means effective at will.

9. In a typewriting machine, the combination with a traveling carriage, of a margin-stop comprising a series of lugs, a lever upon the carriage comprising a lug, a cam upon the carriage adapted to be variably positioned to vary the position of the lever, to cause its lug to variably coöperate with the other lugs to arrest the carriage, a line-space lever for variably positioning the cam, and a device settable to make said lever effective or ineffective at will.

10. In a typewriting machine, the combination with a traveling carriage, of a margin-stop comprising a series of lugs, a lever upon the carriage comprising a lug, a rotatable cam upon the carriage adapted to be variably positioned to vary the position of the lever, to cause its lug to variably coöperate with the other lugs to arrest the carriage, a line-space lever adapted to rotate said cam through a cycle of positions to bring it to successive points and finally to the initial point, and a device settable to make said lever effective or ineffective at will.

11. In a typewriting machine, the combination with a traveling carriage and a line-space lever therefor, of a margin-stop comprising a series of lugs, a coöperating lug upon the carriage, a slide adapted to shift said coöperating lug, and an extension of said slide adapted to be selectively positioned

to cause the line-space lever to be effective or ineffective thereon.

12. In a typewriting machine, the combination with a traveling carriage, a rotatable platen and a line-space lever for turning the platen, of a margin-stop comprising a series of lugs, a coöperating lug upon the carriage, a slide upon the carriage adapted to shift said coöperating lug, an extension of said slide, and a finger-piece connected to said extension adapted to variably position it upon the slide to make the line-space lever effective or ineffective thereon.

13. In a typewriting machine, the combination with a traveling carriage, a rotatable platen and a line-space lever for turning the platen, of a margin-stop comprising a series of lugs, a coöperating lug upon the carriage, a slide upon the carriage adapted to shift said coöperating lug, an extension of said slide, a finger-piece connected to said extension adapted to variably position it upon the slide to make the line-space lever effective or ineffective thereon, a lever upon which said coöperating lug is mounted, a rotatable cam effective on said lug-lever for shifting it, and a pawl-and-ratchet connection between said slide and said cam.

14. In a typewriting machine, the combination with a traveling carriage and a margin-stop for arresting it, of a lever upon which said margin-stop is effective when arresting the carriage, a scale for indicating the position of the lever, and means for positioning the lever in one of a plurality of positions to variably arrest the carriage.

15. In a typewriting machine, the combination with a traveling carriage and a margin-stop for arresting it, of a lever upon which said margin-stop is effective when arresting the carriage, a scale for indicating the position of the lever, a rotatable cam with which said lever is normally in contact, and means for rotating said cam to position the lever according to the scale, to variably arrest the carriage.

16. In a typewriting machine, the combination with a traveling carriage and a margin-stop for arresting it, of a lever upon which said margin-stop is effective when arresting the carriage, a scale for indicating the position of the lever, a rotatable cam with which said lever is normally in contact, means for rotating said cam to position the lever according to the scale, to variably arrest the carriage, a pawl and ratchet for rotating said cam, and a finger-piece for operating said pawl.

17. In a typewriting machine, the combination with a traveling carriage and a margin-stop for arresting it, of a lever upon which said margin-stop is effective when arresting the carriage, a scale for indicating the position of the lever, means for positioning the lever in one of a plurality of posi-

tions to variably arrest the carriage, and a line-space lever adapted to reposition the arresting lever at any operation.

18. In a typewriting machine, the combination with a traveling carriage and a margin-stop for arresting it, of a lever upon which said margin-stop is effective when arresting the carriage, a scale for indicating the position of the lever, a rotatable cam with which said lever is normally in contact, means for rotating said cam to position the lever according to the scale, to variably arrest the carriage, and a line-space lever adapted to reposition the arresting lever at any operation.

19. In a typewriting machine, the combination with a traveling carriage and a margin-stop for arresting it, of a lever upon which said margin-stop is effective when arresting the carriage, a scale for indicating the position of the lever a rotatable cam with which said lever is normally in contact, means for rotating said cam to position the lever according to the scale, to variably arrest the carriage, a pawl and ratchet for rotating said cam, a finger-piece for operating said pawl, a slide of which said finger-piece forms a part, means for selectively positioning said finger-piece, and a line-space lever adapted to operate said pawl and ratchet according to the position of said finger-piece.

20. In a typewriting machine, the combination with a carriage having a front bar, and a margin-stop, of a lug for coöperating with said margin-stop to variably arrest the carriage, and a cam upon said front bar adapted to be variably positioned to position the lug.

21. In a typewriting machine, the combination with a carriage having a front bar, and a margin-stop, of a lug for coöperating with said margin-stop to variably arrest the carriage, a rotatable cam upon said front bar adapted to be variably positioned to position the lug, and a slide lying against said front bar for rotating said cam.

22. In a typewriting machine, the combination with a carriage having a front bar, and a margin-stop, of a lug for coöperating with said margin-stop to variably arrest the carriage, a rotatable cam upon said front bar adapted to be variably positioned to position the lug, a slide lying against said front bar for rotating said cam, and a line-space lever for operating said slide.

23. In a typewriting machine, the combination with a carriage having a front bar, and a margin-stop, of a lug for coöperating with said margin-stop to variably arrest the carriage, a rotatable cam upon said front bar adapted to be variably positioned to position the lug, a slide lying against said front bar for rotating said cam, an extension of said slide, a line-space lever for operating the slide, and means for variably

positioning said extension to determine whether the line-space lever may be effective thereon.

24. In a typewriting machine, the combination with a carriage having a front bar, and a margin-stop, of a lug for coöperating with said margin-stop to variably arrest the carriage, a rotatable cam upon said front bar adapted to be variably positioned to position the lug, a slide lying against said front bar for rotating said cam, a line-space lever for operating said slide, and a pawl and ratchet forming the connection between said slide and said cam.

15 25. In a typewriting machine, the combination with a carriage having a front bar, and a margin-stop, of a lug for coöperating with said margin-stop to variably arrest the carriage, a rotatable cam upon said front bar adapted to be variably positioned to position the lug, a slide lying against said front bar for rotating said cam, an extension of said slide, a line-space lever for operating the slide, means for variably positioning said extension to determine whether the line-space lever may be effective thereon, and a pawl and ratchet forming the connection between said slide and said cam.

26. In a typewriting machine, the combination with a traveling carriage and a margin-stop, of a slide for controlling the effectiveness of the margin-stop upon the carriage, a track upon said slide, a secondary slide settable in said track, a spring-mounted finger-piece comprising a pin adapted to be variably positioned in holes

upon said track to position the secondary slide, and a line-space lever adapted to be effective on the secondary slide in one of its adjusted positions.

27. In a typewriting machine, the combination with a traveling carriage having a front bar, of a margin-stop comprising a series of lugs, a lug movably mounted on said carriage, means, including a cam upon the carriage, for varying the position of the lug on the carriage to determine the lug of the margin-stop to be engaged thereby, means, including a slide lying against said front bar, for rotating said cam, a line-space lever, and means whereby movement of said line-space lever will operate the slide, including a member movable into and out of position to be engaged by the line-space lever.

28. In a typewriting machine, the combination with a carriage, of a margin-stop comprising a series of lugs, a lug mounted on said carriage for movement into positions to engage with different lugs of said series, cam means to determine the position of said lug on the carriage, a line-space lever, and means whereby actuation of said line-space lever will actuate said cam means, including a member movable into and out of position to be engaged by said line-space lever and actuated thereby.
